UNITED STATES PATENT OFFICE.

FRANCIS M. KOCH, OF CANTON, OHIO, ASSIGNOR TO THE REPUBLIC STAMPING & ENAMELING COMPANY, OF CANTON, OHIO, A CORPORATION OF OHIO.

CHARGING FORK FOR ENAMELING FURNACES.

Application filed January 10, 1924. Serial No. 685,434.

To all whom it may concern:

Be it known that I, FRANCIS M. KOCH, a citizen of the United States, and residing at Canton, county of Stark, and State of Ohio, have invented new and useful Improvements 5 in Charging Forks for Enameling Furnaces, of which the following is a specification.

Charging forks such as are commonly used for placing the ware in enameling furnaces 10 and removing the ware therefrom, are ordinarily manually operated by the "burner," making it necessary for him to first open the furnace door and then manually push the fork into the furnace, lowering or rais- 15 ing the same after it has reached the proper position within the furnace to either deposit new ware upon the hearth of the furnace or remove burnt ware therefrom. The "burner" is thus exposed to excessive heat 20 during the charging and unloading of the furnace.

It is also customary in operating the usual form of charging forks for the "burner" to first manually open the furnace door and 25 then move the fork into the furnace to charge or unload the same, after which he manually withdraws the fork from the furnace and then closes the door. This operation causes a considerable waste of heat from the furnace 30 as the door is necessarily left open for a considerable period during the operation of the charging fork.

The objects of the present invention are to overcome the above difficulties by provid- 35 ing a charging fork which is automatically operated to open the door only during the time the fork is actually passing into or out of the furnace and to automatically move the loaded fork into the furnace, lower- 40 the same to deposit the ware upon the hearth of the furnace, and automatically withdraw the fork from the furnace, the fork remaining in the lowered position until it is desired to withdraw the burnt ware from the 45 furnace, when the fork is again automatically moved into the furnace, raised to lift the ware from the hearth, and withdrawn from the furnace, the fork being automatically stopped after the ware is withdrawn.

50 A further object is to provide means for automatically turning off the gas or oil burners during the time the ware is in the furnace, automatically turning the burners

on when the ware is withdrawn from the furnace.

A still further object is to provide charging forks of this character which the "burner" may operate at a distance from the furnace, obviating the necessity of exposing himself to the extreme heat of the 60 open furnace as he charges or unloads the same.

The above and other objects are attained by constructing the charging forks in the manner illustrated in the accompanying 65 drawings, in which—

Figure 1, is a side elevation of a charging fork and a portion of a furnace showing the fork loaded with ware and in position to be moved into the furnace;

Fig. 2, a top plan view of the carriage from which the fork is suspended, showing a portion of the track in broken lines;

Fig. 3, a section on the line 3—3, Fig. 2;

Fig. 4, a section on the line 4—4, Fig. 2; 75

Fig. 5, a section on the line 5—5, Fig. 1;

Fig. 6, a perspective view of the fork rais- 70 ing and lowering mechanism upon the car- rige;

Fig. 7, a detail sectional view of a portion 80 of the trip mechanism for operating the raising and lowering of the fork; and

Fig. 8, a diagrammatic view of the electric wiring of the device.

Similar numerals of reference refer to 85 corresponding parts throughout the drawings.

A furnace of usual construction is indicat- 90 ed generally at 1, provided with the heating chamber 2, having a vertically sliding door 3 for closing the same, the hearth 4 having the longitudinal abutments 5 at opposite sides thereof to support the racks 6 upon which the ware, indicated at 7, is carried.

The door 3 of the furnace is mounted for 95 vertical reciprocation upon the upright guides 8, one of which is elongated above the door, and provides a fulcrum as at 9 for a lever 10 one end of which is connected to the cable 11 which is attached to the upper end of the door as by the lug 12, a cable 13 being suspended from the other end of the lever and supporting the counter weight 14.

A frame work comprising the uprights 105 15, the track members 16 and horizontal

end members 17, is mounted in alignment with the furnace and supports the carriage indicated generally at 18, which is provided with the front and rear flanged wheels 19 and 20 respectively, mounted to travel upon the tracks 16.

The front wheels are fixed upon a shaft 21 upon which is mounted a worm gear 22 meshing with the worm 23 upon the shaft 10 of the motor 24 which is supported upon the forward portion of the carriage.

The fork 25 is carried at the lower end of a vertically slidable frame comprising the vertical, rectangular portion 26 and the 15 rearwardly inclined brace members 27 connected to the upper end of the rectangular portion of the frame and joined at their lower ends by the cross piece 28 upon which the rear ends of the fork members 25 are 20 supported.

This frame is provided with the rollers 29 and 30 which engage opposite sides of the vertical guide members 31 suspended from the carriage 18. A rack bar 32 is connected to the upper portion of the reciprocating frame and meshes with a pinion 33 mounted upon a shaft 34.

A pulley 35 is fixed upon the shaft 34 and the ends of the cables 36 are connected 30 to said pulley and extend outward in opposite directions over the pulleys 37 supporting the counter weights 38 which are slidably mounted upon the vertical guide rods 39.

35 A motor 40 is mounted upon the carriage and provided with a worm 41 upon its shaft, said worm meshing with the worm gear 42 upon the shaft 43 which is journaled in bearings 44 supported upon the carriage.

40 An eccentric 45 is fixed upon the shaft 43, an eccentric band 46 being located around said eccentric and connected by means of the link 47 with the vertically reciprocating frame 26—27. Thus as the 45 shaft 43 is rotated the reciprocating frame which supports the fork will be raised and lowered by means of the eccentric and link.

A lever 50 is pivoted, near one end, to a 50 stationary portion of the frame as shown at 51, the opposite end being connected to the cable 13 which supports the counter weight 14. The other end of the lever is provided with a stud 52 arranged to move in the upper or lower cam tracks, 53 and 54 respectively, which are formed in a member 55 supported upon one side of the carriage.

55 A finger 56 is pivoted as at 57 upon the member 55, by any suitable means which will frictionally hold the finger in either position into which it is moved, a pair of pins 58 and 59 being provided in the member 55 for limiting the movement of the finger 56 in either direction. It will be seen that as this finger is moved into the upper position, 60 or against the pin 58, it closes the forward

end of the upper cam track 53 and when moved into the lower position or against the pin 59 it closes the entrance to the lower cam track 54, thus guiding the stud 52, upon the lever 50, into either of the cam 70 tracks as desired.

A similar finger 60 is located at the rear end of the member 55 for closing the entrance to the upper or lower cam tracks as desired, pins 61 and 62 limiting the movement of the finger 60 in either direction.

This last named finger is fixed upon a shaft 63 which is journaled through the member 55 and provided with a rocker arm 64 through the end of which the headed rod 65 is slidably mounted, springs 66 and 67 being located around said rod upon opposite sides of the rocker arm 64, the spring 66 engaging the head upon the rod while the spring 67 engages the lever 68 which is 80 connected to the lower end of the rod, and pivoted intermediate its extremities as at 69 to a suitable portion of the carriage, the free end of said lever being slotted, as shown at 70, to receive the rod 71 which is 90 carried by the vertically reciprocating frame 26—27.

The line wires, leading from any suitable source of electric supply, are shown at 72 and 73 and are connected to the trolley wires 74 and 75 respectively, the trolley wheels 76 and 77 mounted upon the carriage being arranged to engage the trolley wires 74 and 75 respectively. A manually operated switch 78 is located in the line 74.

The trolley wheel 76 is connected by a wire 79 with a switch point 80 upon the carriage and with a contact 81 upon the switch blade 82, said contact being insulated from the contact 83 at the other end of said switch blade. A wire 84 leads from the switch point contact 83 to the motor 24, a wire 85 connecting the trolley wheel 77 with said motor. A wire 86 connects the wire 85 with the raising and lowering motor 40, which is 110 also connected by a wire 87 with the switch point 88 arranged to be engaged by the contact 81 of the switch blade.

The switch blade 82 is carried upon a lever 89, pivoted as at 90 upon the carriage 115 and connected by a slotted link 91 with the lever 92 which is pivoted as at 93 upon the carriage. The elongated slot 94 in the link 91 is engaged by the pin 95 upon the lever 92.

A pair of contacts 96 and 97 are insulated 120 from each other and carried by the lever 92, and are connected by the wires 98 and 99 respectively with the motor 24. Wires 100 and 101 lead from the motor 24 to the switch points 102 and 103 respectively, the switch point 104 being also connected to the wire 100.

A reversing switch is thus provided for reversing the motor 24 as the motor will run in one direction when the contacts 96 and 125 130

97 are in engagement with the switch points 102 and 103 respectively, as shown in Fig. 8, and will run in the opposite direction when these contacts engage the switch points 103 and 104 respectively.

10 A stud 105 is fixed upon the carriage for engagement with the manually operated switch to open the same when the carriage moves back to the normal position, and a stud 106 is fixed upon the frame for engagement with the lever 89 to operate the switch blade 82 when the carriage moves to the forward extent of its movement. A finger 107 is fixed upon the frame in position to engage the lever 92 when the carriage reaches the normal position to throw the reversing switch 96-97 into the position shown in Fig. 8.

15 A lever 108 is pivoted as at 109 upon the carriage and provided with a depending finger 110 which is normally held out of engagement with the switch blade 82 by the means of a spring 111. The other end of this lever is arranged to be engaged by the studs 112 which are diametrically oppositely located upon the worm gear 42.

20 The pipe 113, which supplies oil or gas fuel to the furnace is provided with a valve 114, the valve stem 115 thereof having a bell crank 116 fixed thereon, a weight 117 being suspended from one arm of the bell crank, the other arm thereof being connected by a rod 118 with one arm of a bell crank 119, pivoted as at 120 upon the frame. The other arm of this bell crank has a depending finger 121 arranged to be engaged by the finger 122, carried by the vertically reciprocating frame 26-27, when the same is in the raised position.

25 The operation of the device is as follows: With the parts in the position shown in Figs. 1 and 8, the fork is in the initial or normal position, ready for charging the furnace, the switch 78 being open, the motors stopped and the vertically reciprocating frame 26-27 in the raised position holding the fork in the upper or initial position.

30 The ware 7, resting upon the racks 6, is placed upon the fork and the switch 78 is manually closed. The circuit is thus closed, through the switch point 80 and contact 83, to the motor 24, the reversing switch being in position to operate said motor, in a direction to move the carriage forward or toward the furnace.

35 As the carriage starts its forward movement the pin 52 upon the lever 50 will travel through the cam slot 53, the forward end of the lever 50 being moved downward pulling the cable 13 downward and rocking the lever 10 to raise the door of the furnace sufficiently to clear the ware 7 as the fork moves into the furnace. As the carriage reaches the forward limit of its movement, that is when the ware is entirely within the fur-

nace, the lever 89 will be engaged by the stud 106 rocking the switch blade 82 into the position opposite from that shown in Fig. 8, breaking the contact at 80-83 and closing the contact at 81-88, thus breaking the circuit to the motor 24 and closing the circuit to the raising and lowering motor 40. The fork will then be lowered by the lowering operation of the vertically reciprocating frame 26-27 through the eccentric 45.

40 As this action takes place one of the pins 112 will engage the lever 108 rocking the same, the finger 110 thereof engaging the switch blade 82 and throwing the same back into the position shown in Fig. 8. The circuit is now broken through the motor 40 and again closed through the motor 24 and the reversing switch to said motor being in the position opposite to that shown in Fig. 8, the carriage will be moved backward, leaving the ware deposited upon the hearth in the manner shown in Fig. 5, the fork being withdrawn from the furnace in lowered position.

45 It should be noted that as the vertically reciprocating frame 26-27 is lowered, the lever 70 is rocked, throwing the switching finger 60 into the raised position, causing the pin 52 upon the lever 50 to travel back through the lower cam slot 54. It will be seen that the door is thus lowered sufficiently to just permit the empty fork to be withdrawn, and after the fork is entirely withdrawn, the pin 52 traveling down through the forward inclined end of the cam slot 54 entirely closes the door, at the same time raising the switching finger 56 so as to permit the pin 52 to again travel back through the lower cam track upon the next operation of the carriage.

50 As the carriage reaches the initial position the switch 78 will be opened by the stud 105 and the reversing switch will be thrown into the initial position, as shown in Fig. 8, by means of the finger 107. The frame 26-27 being in lowered position, the finger 122 thereon will not engage the finger 121 of the bell crank 119. The weight 117 will thus hold the valve 114 in closed position. This is essential in the baking of enameled ware as the burners must be shut off during the time the ware is in the furnace to prevent soot from marring the ware.

55 When the ware is properly burned the operator again closes the switch 78 starting the carriage forward, opening the door just sufficiently to permit the empty fork to pass under the same. As the carriage reaches the forward limit of its movement the motor 24 will be again stopped and reversed, as above described, and the motor 40 operated, raising the frame 26-27, the fork thus engaging the racks 6 upon which the burnt ware is carried, lifting the same free of the hearth, at which point the switch

blade 82 will be automatically reversed, as above described, stopping the motor 40 and starting the motor 24 in the reverse direction, moving the carriage back to the normal position, withdrawing the fork in the raised position with the burnt ware thereon, further opening the door just sufficiently to permit the ware to pass out of the furnace, after which the door is entirely closed.

10 As the carriage again reaches the normal position the manually operated switch 78 will again be opened by the stud 105 stopping the carriage. The vertically reciprocating frame 26-27 being in the raised position, the finger 122 thereof will engage the finger 121 of the bell crank 119, as shown in Fig. 6, opening the valve 114, turning on the gas or oil burners and properly heating the furnace until the next operation of the fork 20 to carry new ware into the furnace, as above described.

I claim:

1. A charging fork for furnaces including means for moving the fork into the furnace, 25 cooperating mechanism set in operation by said inward movement of the fork, for automatically moving the fork vertically within the furnace, and cooperating mechanism set in operation by said vertical movement of the fork for automatically withdrawing the fork from the furnace.

2. A charging fork for furnaces including means for moving the fork into the furnace, cooperating mechanism set in operation by said inward movement of the fork for automatically moving the fork vertically within the furnace, cooperating mechanism set in operation by said vertical movement of the fork for automatically withdrawing the fork from the furnace, and means operated by the withdrawing movement of the fork for automatically stopping the fork after it is withdrawn from the furnace.

3. A charging fork for furnaces including 45 means for moving the fork into the furnace, cooperating mechanism set in operation by said inward movement of the fork for automatically raising the fork within the furnace, and cooperating mechanism set in operation by said raising movement of the fork for automatically withdrawing the fork in raised position.

4. A charging fork for furnaces including 55 means for moving the fork into the furnace, cooperating mechanism set in operation by said inward movement of the fork for automatically lowering the fork within the furnace, and cooperating mechanism set in operation by said lowering movement of the fork for automatically withdrawing the fork in lowered position.

5. A charging fork for furnaces including 60 means for moving the fork into the furnace, cooperating mechanism set in operation by said inward movement of the fork for au-

tomatically lowering the fork within the furnace, cooperating mechanism set in operation by said lowering movement of the fork for automatically withdrawing the fork in lowered position, and mechanism operated 70 by said withdrawing movement of the fork for automatically stopping the fork after it is withdrawn from the furnace.

6. A charging fork for furnaces including means for moving the fork into the furnace, 75 cooperating mechanism set in operation by said inward movement of the fork for automatically raising the fork within the furnace, cooperating mechanism set in operation by said raising movement of the fork 80 for automatically withdrawing the fork in raised position, and mechanism operated by said withdrawing movement of the fork for automatically stopping the fork after it is withdrawn from the furnace.

7. A charging fork for furnaces including 85 means for moving the fork into the furnace, cooperating mechanism set in operation by said inward movement of the fork for automatically lowering the fork within the furnace, cooperating mechanism set in operation by said lowering movement of the fork for automatically withdrawing the fork in lowered position, means for again moving the fork into the furnace in lowered position, 90 cooperating mechanism set in operation by said inward movement of the fork in lowered position for automatically raising the work within the furnace, and cooperating mechanism set in operation by said raising movement of the fork for automatically withdrawing the fork from the furnace in 95 raised position.

8. A charging fork for furnaces including 100 means for moving the fork into the furnace, cooperating mechanism set in operation by said inward movement of the fork for automatically lowering the fork within the furnace, cooperating mechanism set in operation by said lowering movement of the fork for automatically withdrawing the fork in lowered position, means for again moving the fork into the furnace in lowered position, 105 cooperating mechanism set in operation by said inward movement of the fork in lowered position for automatically raising the fork within the furnace, cooperating mechanism set in operation by said raising movement of the fork for automatically withdrawing the fork from the furnace in raised position.

9. A charging fork for furnaces including 110 means for moving the fork into the furnace, 115 cooperating mechanism set in operation by said inward movement of the fork for automatically lowering the fork within the furnace, cooperating mechanism set in operation by said lowering movement of the fork for automatically withdrawing the fork in raised position, and mechanism operated by said withdrawing movement of the fork in raised position for automatically stopping the fork after it is withdrawn from the furnace.

- by said lowering movement of the fork for automatically withdrawing the fork in lowered position, mechanism operated by said withdrawing movement of the fork for automatically stopping the fork after it is withdrawn from the furnace, means for moving the fork into the furnace in lowered position, cooperating mechanism set in operation by said inward movement of the fork in lowered position for automatically raising the fork within the furnace, cooperating mechanism set in operation by said raising movement of the fork for automatically withdrawing the fork in raised position, and mechanism operated by said withdrawing movement of the fork in raised position for automatically stopping the fork after it is withdrawn from the furnace.
10. In combination with a furnace having a door, a charging fork including means for moving the fork into the furnace, cooperating mechanism set in operation by the inward movement of the fork for automatically opening the door as the fork is moved toward the furnace, cooperating mechanism set in operation by the inward movement of the fork for automatically lowering the fork within the furnace, cooperating mechanism set in operation by the lowering movement of the fork for automatically withdrawing the fork in lowered position, and mechanism operated by the withdrawing movement of the fork for automatically closing the door as the fork is withdrawn.
11. In combination with a furnace having a door, a charging fork including means for moving the fork into the furnace, cooperating mechanism set in operation by said inward movement of the fork for automatically opening the door as the fork is moved toward the furnace, cooperating mechanism set in operation by the inward movement of the fork for automatically lowering the fork within the furnace, means for partially closing the door as the fork is lowered, cooperating mechanism set in operation by the lowering movement of the fork for automatically withdrawing the fork in the lowered position, and means operated by the withdrawing movement of the fork for entirely closing the door as the fork is withdrawn.
12. In combination with a furnace having a door, a charging fork including means for moving the fork into the furnace, cooperating mechanism set in operation by the inward movement of the fork for partially opening the door as the fork is moved toward the furnace, cooperating mechanism set in operation by the inward movement of the fork for automatically raising the fork within the furnace, cooperating mechanism set in operation by the inward movement of the fork for automatically withdrawing the fork in raised position, and mechanism operated by the withdrawing movement of the fork for automatically closing the door as the fork is withdrawn.
13. In combination with a furnace having a fuel controlling valve, a charging fork including means for moving the fork into the furnace, cooperating mechanism set in operation by the inward movement of the fork for automatically raising the fork within the furnace, cooperating mechanism set in operation by the raising movement of the fork for automatically withdrawing the fork in raised position and means controlled by the withdrawal of the fork for automatically opening the valve as the fork is withdrawn.
14. In combination with a furnace having a fuel controlling valve, a charging fork, means for moving the charging fork into the furnace in raised or lowered position, means for moving the charging fork vertically within the furnace, means for withdrawing the fork in raised or lowered position and means for automatically opening the fuel valve when the fork is withdrawn in raised position.
15. In combination with a furnace, a carriage mounted in front of the furnace, a charging fork carried by the carriage, a motor for operating the carriage toward and from the furnace, a motor for raising and lowering the fork, a reversing switch for the first named motor and automatic means for stopping the carriage operating motor at a predetermined time, starting the raising and lowering motor, operating the reversing switch, stopping the raising and lowering motor and operating the carriage operating motor.
16. In combination with a furnace, a carriage mounted in front of the furnace, a charging fork carried by the carriage, a motor for operating the carriage toward and from the furnace, a motor for raising and lowering the fork, a reversing switch for the first named motor and automatic means for stopping the carriage operating motor at a predetermined time, starting the raising and lowering motor, operating the reversing switch, stopping the raising and lowering motor and operating the carriage operating motor, and stopping the carriage operating motor at a predetermined time.

In testimony that I claim the above, I have hereunto subscribed my name.

FRANCIS M. KOCH.
